RAILROAD TIE

Filed March 26, 1928

INVENTOR.
Louis T. Botto,

BY *John W. Spellman*
ATTORNEY.

UNITED STATES PATENT OFFICE.

LOUIS T. BOTTO, OF SAN ANTONIO, TEXAS.

RAILROAD TIE.

Application filed March 26, 1928. Serial No. 264,713.

This invention involves improvements in railroad-ties and the object of this invention is to produce a railroad-tie composed of several metal sections and concrete or some other cementing material, combined in such a way that it can be fabricated in place under the railroad rails if desired, into a railroad tie more economical in first cost, maintenance, and replacement, and rendering the same service now obtained from wood ties, composition, or fabricated ties.

With the foregoing, and other objects in view which will appear in the following description, and with the understanding that the invention lies in the uses of the component parts and not in the particular embodiment herein disclosed, and that changes may be made in this particular embodiment without departing from the spirit of the invention.

One embodiment of my invention is illustrated in the accompanying drawings in which Figure 1 is a perspective view of my improved tie showing angle iron brace members,

Figure 2 is an end view,

Figure 3 is a section taken on line 3—3 of Figure 4,

Figure 4 is a plan view,

Figure 5 is a side elevation,

Figure 6 is a perspective view showing tie with cross plates on which rails rest, and

Figure 7 is a view of the reinforcing wire.

The railroad-tie shown is constructed of two rail sections, 1, cut to the proper length and laid parallel and in the same plane, with the proper distance between the adjacent edges of the bases of the rails. This distance varies with the weight and sections of the metal members and the strength of the reinforcing wire and the concrete or cement material used, and in all cases is the maximum allowable distance, taking into consideration proper factors of safety consistent with permanent construction. In special cases, of course, this distance can be made less than that set out in the preceding sentence.

Likewise any suitable metal member can be used in place of the rail sections, 1, as shown.

The purpose of this maximum spacing is to obtain the greatest width of tie possible with the materials used, so that a maximum bearing surface is obtained, thereby decreas-

ing the number of ties necessary to meet certain road bed conditions to a minimum. This is one of the salient features of this invention.

The bracing members, 2, are next cut to such a length as to extend across the whole width of the tie. Angle iron as shown in Figs. 1 to 5 inclusive, may be employed for this purpose, or flat plates of suitable dimensions may be used. Likewise plates 3 placed above sections, 1, to lie directly under the base of the railroad rail crossing the tie, as shown in Fig. 6, may be used instead of the angle iron as shown in the other figures. These members are welded to the sections, 1, as shown, in sufficient places to attain the strength desired. If it is deemed necessary, holes may be burned into the members, 2, as shown at 4, before these members are put in place, and then welded to the sections, 1, through these holes also.

The reinforcing wire, 5, and shown in detail in Fig. 7, is placed as shown at 5 in Fig. 3. The position or actual type of reinforcing steel used may be changed to obtain the maximum strength for the use intended. The purpose of this reinforcing steel is to increase the strength of the concrete or cement material, 6, which is poured between the sections, 1, as shown.

After the sections, 1, and 2, are in position in the road-bed and properly aligned, and the railroad rails are laid thereon, the holes, 7, are drilled or burned as shown, if standard clips bolted on are desired to fasten the rails to the cross-ties. However, instead of bolting the clips in place, these same clips may be welded to the top of the sections, 1. The idea of welding the clips to the tie is claimed as new and novel, and is included as one of the features of this invention.

Another important feature, which is claimed and included as part of this invention, is the fact that all the elements used in the construction of this tie may be brought to the place, where the tie is to be used, separately, and made into the proper dimensions and assembled in place in the road-bed, allowing the concrete or a cement-like material to be poured from the top after it is in position, and eliminating all heavy railroad-ties.

This feature permits these ties to be made

up in any lengths desired, even for switches, and double track construction, and still be practicable.

Another feature of this invention is brought out in the case where steel plates 3 are used to weld the two parallel sections, 1, together. These plates may be placed so that their centers are under the center of the railroad rail crossing. In this event 10 these plates also serve as tie plates. Tie plates are not used with the other forms of this tie.

Having described my invention, what I claim as new and novel, and desire to secure by Letters Patent, is:—

A fabricated railroad cross-tie comprising two sections of track rails in spaced parallel relation to each other, said sections being inverted and having their normally 20 lower wide base flanges uppermost and their normally upper narrow wheel engaging flanges lowermost, rail supporting plates welded to the upper side of said uppermost flanges, angle irons comprising horizontal

and vertical walls positioned at opposite ends 25 of said sections, said horizontal walls of said angle irons extending across and contacting with the tops of said sections so as to lie above said sections, said vertical walls of said angle irons extending across and 30 contacting the ends of said sections, both the said horizontal and vertical walls of the said angle irons being welded to said rail sections in sufficient places to attain the strength desired without utilizing any other 35 member for rigidly holding said sections together and for preventing relative inward or outward movement of said sections at both the upper and lower portions thereof, the space between said sections being filled 40 by a concrete body, a steel reinforcement embedded in said concrete and spaced from said sections, said concrete and said reinforcement constituting the only substances 45 in the space between said sections.

In testimony whereof I affix my signature.

LOUIS T. BOTTO.
